WILHELM RESCH, OF BINNINGEN, NEAR BASEL, SWITZERLAND, ASSIGNOR TO
ALEXANDER CLAVEL, OF BASEL, SWITZERLAND.

PROCESS FOR DYEING, BLEACHING, OR LIKE TREATMENT OF COPS.

1,317,220.

Specification of Letters Patent. Patented Sept. 30, 1919.

Application filed July 2, 1918. Serial No. 243,072.

To all whom it may concern:

Be it known that I, WILHELM RESCH, a citizen of the Swiss Republic, and resident of Binningen, near Basel, Switzerland, have 5 invented new and useful Improvements in Processes for Dyeing, Bleaching, or like Treatment of Cops, of which the following is a full, clear, and exact specification.

In dyeing, bleaching or like treatment of 10 cops by means of a circulating liquid it is known practice to mount the cops on metal or rubber spindles and so to pack them that the channels produced by this mounting are stopped up by filling material so that there 15 may be uniform dyeing or bleaching of the textile material. It is also known practice in dyeing cops without spindles to press them closely together. Hitherto the preliminarily pressed cops have been packed on the 20 perforated bottom of the container in such a way that the circulating liquid must pass through the packed cops in a direction at right angles to their longitudinal axes. Or the packing and pressing of the cops has 25 been performed in the container upon the perforated bottom and the container has been so placed that the liquid must pass through the cops in the longitudinal direction.

30 The present invention relates to the packing and treatment of the cops in the last-named manner. In the known procedure, whether in consequence of insufficient pressure or in consequence of incorrect application 35 of the cops to the perforated walls of the container, an irregular treatment of the cops in the pack is to be expected. According to this invention a thoroughly uniform treatment of the pack is obtained by packing 40 and pressing together the cops on their paper tubes in layers in the container on an unperforated bottom, their treatment with the liquid being in the longitudinal direction between perforated ends of the container, and for insuring the position of the 45 outside cops in the container there is inserted in the end of the paper tube of the cops a short stopper before the packing operation. This stopper forms a retainer for the yarn 50 and a protection for the end of the cop tube. This kind of packing and treatment renders possible a firm and permanently unalterable as well as uniform pressing together of the cops, without additional packing, and prevents 55 the formation of empty spaces or dead corners which give rise to irregular passage of the liquid. There is thus obtained throughout the whole a tightly closed packing and even at the extreme ends of the cops a thoroughly uniform treatment of the 60 latter.

After the treatment of the textile material with the circulating liquid the container may be withdrawn and passed to the centrifugal machine for centrifuging its contents. 65

The accompanying drawing illustrates the process in use on an apparatus for practising the same. Figure 1 is a vertical section through the apparatus; Fig. 2 shows in side elevation a portion of the packing 70 on an enlarged scale and Fig. 3 is an end elevation thereof.

The pack container *a* is packed with cops to be treated, outside the apparatus in which the treatment is to occur. For this purpose 75 it is placed on the unperforated side wall which is to the right hand in Fig. 1 upon a support and the cops are laid in it in the horizontal position in layers and pressed transversely to their longitudinal axes, so 80 that they finally form a packing in which all passages between the several cops as well as the longitudinal openings of their paper tubes are tightly closed. A part of this packing is shown in Figs. 2 and 3 drawn 85 to an enlarged scale, from which the mode of laying and pressing together the cops *b* will be apparent. Before the packing those cops which are to abut against the perforated end walls *c* and *d* of the container are 90 provided with small short stoppers *e* which are stuck into the openings of the cop tubes in order to serve as a retainer for the yarn and as a protection for the end of the paper tube as well as to close the opening. These 95 stoppers also serve for insuring the position of the cops in the container during the centrifuging of the pack. When the cops have been packed into the container *a* the latter, turned through an angle of 90°, is inserted 100 into the vat *f* with its perforated end walls *c*, *d* between two filter chambers *g*, *h*, Fig. 1, and the cover *i* of the upper filter chamber *g*, the walls of which are in part arranged against the container *a* itself, is firmly pressed down so as to render tight the side packing of the filter chambers. The necessary pressure on the cover *i* may be exerted for example by means of the cover *k* and screw bolts *k'*. 105 110

The closed vat *f* which is provided with the usual accessories, such as a pressure gage, safety valve and the like, is fed at *m* with the liquid under pressure. The liquid is driven from the above downward through the stationary cops *b* in the longitudinal direction of the latter and through the filter chambers *g*, *h* and leaves the vat *f* at *n*. The perforated end walls *c*, *d* of the container distribute the liquid uniformly over the pack and the uniform tight compression of the cops, by means of which all intermediate passages and all dead spaces in the pack for the direct passage of the liquid are closed, insures a uniform saturation of the fibrous material throughout. When the treatment is complete, the container *a* with the goods in it is removed from the vat *f* and as may be necessary is passed to the centrifugal machine for the purpose of centrifuging the goods.

What I claim is:

A process for dyeing, bleaching and the

like of cops by means of a circulating liquid, consisting in using a container with opposite perforated walls, packing the cops therein under pressure upon an unperforated side wall of the container after having inserted short safety stoppers into the socket openings of the outside cops so that the cops extend perpendicularly to said perforated walls of the container, then introducing the container with its perforated walls between a liquid supplying head and a liquid discharging head of a treating chamber and causing the liquid to flow through said heads and longitudinally through the cops of the packing in the container, substantially as and for the purpose described.

In witness whereof I have hereunto signed my name this 4th day of June, 1918, in the presence of two subscribing witnesses.

WILHELM RESCH.
